US00D749713S

(12) **United States Design Patent**
Guyuron et al.

(10) **Patent No.:** **US D749,713 S**
(45) **Date of Patent:** **** Feb. 16, 2016**

(54) **HEAT EXCHANGER**

(71) Applicant: **Innovative Medical Equipment, LLC**,
Lyndhurst, OH (US)

(72) Inventors: **Bahman Guyuron**, Lyndhurst, OH
(US); **Fred Bahr**, Seven Hills, OH (US);
Brad A. Pulver, Shaker Heights, OH
(US); **Jamie Horvath**, Twinsburg, OH
(US); **Glen M. Guyuron**, Lundhurst, OH
(US)

(73) Assignee: **Innovative Medical Equipment, LLC**,
Lyndhurst, OH (US)

(**) Term: **14 Years**

(21) Appl. No.: **29/498,081**

(22) Filed: **Jul. 31, 2014**

(51) LOC (10) Cl. **23-03**

(52) U.S. Cl.

USPC **D23/314**

(57) **CLAIM**

The ornamental design for a heat exchanger, as shown and described.

DESCRIPTION

FIG. 1 is a perspective view of a heat exchanger showing our new design.

FIG. 2 is a top view thereof.

FIG. 3 is a bottom view thereof.

FIG. 4 is a rear view thereof.

FIG. 5 is a front view thereof.

FIG. 6 is a left side view thereof.

FIG. 7 is a right side view thereof.

FIG. 8 is a perspective view of another embodiment of the heat exchanger.

FIG. 9 is a top view thereof.

FIG. 10 is a bottom view thereof.

FIG. 11 is a rear view thereof.

FIG. 12 is a front view thereof.

FIG. 13 is a left side view thereof; and,

FIG. 14 is a right side view thereof.

The broken line shown in the drawings are for the purpose of illustrating portions of the article that form no part of the claimed design.

1 Claim, 4 Drawing Sheets
